UNITED STATES PATENT OFFICE

1,934,296

FUEL INJECTION UNIT

Hermann I. A. Dorner, Detroit, Mich., assignor,
by mesne assignments, to Packard Motor Car
Company, Detroit, Mich., a corporation of
Michigan

Application May 22, 1929. Serial No. 365,094

2 Claims. (Cl. 299—107.2)

The invention relates to internal combustion engines of that type generally designated as Diesel and in which the fuel is injected at high pressure into a body of compressed air in the combustion chamber. It is the object of the invention to obtain a construction of fuel injection unit which as such is attachable to the cylinder of the engine and which comprises the nozzle, a pump and a fuel supply connection. It is a further object to obtain a construction of unit so organized as to obtain uniformity in operation with accurate control of the quantity of fuel injected, even where this is exceedingly minute. Still further, it is an object to obtain a construction adapted for commercial manufacture and composed of comparatively few elements of simple construction. With these and other advantages in view, the invention consists in the construction as hereinafter set forth.

In the drawing:

Figure 1 is a section through a portion of the engine cylinder showing my improved fuel injection unit applied thereto and in longitudinal section;

Figure 2 is a sectional plan view on line 2—2 of Figure 1;

Figures 3 and 4 are transverse sections respectively on lines 3—3 and 4—4 of Figure 1.

In the operation of internal combustion engines of the type above referred to and particularly in connection with cylinders having relatively small piston displacement and designed for high speed engines, it is of the utmost importance first to accurately control the quantity of fuel injected; second, to inject the fuel in a finely divided form or spray; third, to prevent clogging or stoppage in the fuel line, and fourth, to provide for a relatively large range of variation in the quantity of fuel used for correspondingly carrying the power and speed of the engine. My improved fuel injection unit is adapted to fulfill these conditions, first, by a nozzle construction adapted to finely spray injected fuel while avoiding all danger of clogging; second, in rigidly connecting to this nozzle and as close as possible to the point of discharge, the fuel injection and measuring pump; third, in supplying this pump with fuel which has been freed as far as possible from all clogging impurities as well as from air or gas bubbles. The specific construction of some of these elements has formed the subject matter of other patents taken out by me, including Nos. 1,690,893 of November 6, 1928 and 1,628,657 of May 17, 1928. The present invention, however, relates to the novel combination and organization

of these and other elements as hereinafter described.

As specifically shown, A is a rigid casing member adapted to be rigidly secured to the engine cylinder by suitable means such as the laterally extending flanges B and the bolts C for clamping said member to a lug or bearing D on the cylinder. The casing A is bored on an axis perpendicular to the cylinder axis and is counter-bored and threaded at its inner end to receive the nozzle member E projecting through an aperture in the lug D to the interior of the cylinder. The outer end of the casing A is also counter-bored and threaded to receive a threaded plug or bushing F which in turn is bored and threaded to receive an adjustable threaded rod or stop member G. The plug F is fashioned at its inner end to form a packing flange surrounding a smooth inwardly projecting shank G' of the member G.

The nozzle E is provided at its inner end with a flaring conical mouth portion E' within which is arranged a knife edge yieldable sprayer valve H formed at the end of a shank H' extending through the nozzle and into the bore within the member A. The inner end of the shank H' is threaded to receive a collar I forming an abutment for one end of a spring J which is sleeved about said shank, the opposite ends of said spring abutting against a bearing on the nozzle E. A cap nut K engaging the threaded end of the shank H' serves to lock the collar I and also forms a bearing for abutting against the stop member G, the arrangement being such that by adjustment of the collar I and cap nut K the spring J may be properly tensioned and by adjustment of the stop member G the knife edge H may be arranged in very close proximity to the conical portion E' of the nozzle but without actually contacting the same. The angle of the conical nozzle portion E' is greater than the angle of the conical portion forming the knife edge H so that these two surfaces are non-parallel and the closest point of proximity is at the knife edge. Thus the liquid fuel which is ejected from the nozzle must pass between the knife edge and the conical surface E' which parts are held together by the relatively heavy pressure of the spring J. If, however, the pressure of the liquid fuel is sufficient and its speed of ejection too fast to pass through this restricted space, the spring J will yield, permitting a wider separation.

Projecting laterally from the casing member A is an integral threaded nipple A' through which a tubular casing L may be rigidly attached

to said member A. The member L contains the pump cylinder or barrel M which is inserted therein from the end engaging the nipple and which has a head M' engaging a shoulder within 5 the tubular casing. The pump barrel M at its head end is counter-bored to form a conical seat M² for a ball check valve N controlling the outlet of the liquid fuel from the barrel. For greater certainty in action I preferably provide a double 10 check valve and to this end there is inserted within the tubular casing L and between the head M' and the nipple A' a bushing O having a conical seat O' for a second ball check valve N'. Springs P and P' are arranged to yieldably hold the check 15 valves N and N' normally to their respective seats, said springs abutting respectively on the shoulder O² within the bushing O and a shoulder within the nipple A'. A fluid passageway A² extends through the nipple to the bore in the member A, 20 thus establishing communication between the pump barrel and the nozzle.

As shown in Figures 1 and 3, the portion of the tubular casing L surrounding the upper portion of the barrel M is formed externally with 25 conical seats Q, Q' separated by an annular recess Q². These seats are adapted to receive corresponding conical bearings on an annular member R which may be sleeved upon the member L and clamped to its seat by a nut S. Thus there is 30 formed between members L and R an annular channel surrounding the barrel M and communicating therewith through registering ports L' M³. The annular member R has an annular recess between the portions engaging the bearings Q, Q' 35 within which is arranged an annular screen T. The screen T is of a diameter somewhat greater than that of the conical bearing Q' so as to permit of being sleeved over said bearing with the member R. There are also gaskets T' T² at opposite ends of the screen which bear against the member R and form a sealing contact therewith leaving an annular space T³ therebetween. On one side of the member R is a transversely extending open ended channel R' intersecting the 40 annular space T³ so as to be in free communication therewith. At opposite ends of the channel R' are hollow fittings U which are clamped to the member R by a central rod V threaded at its opposite end to engage clamping nuts V'. Gaskets 45 U' are arranged to seal between the fitting U and the member R and also between said fittings and clamping nuts V. The fittings U are connected to conduits W which lead from the source of supply for the liquid fuel and also between different cylinders of a multi-cylinder unit. Thus the fuel 50 which is supplied by a low pressure pump (not shown) will pass through the channels R' of each fuel injection unit of a multi-cylinder engine, while the fuel used by each unit will enter by way of the annular passage T³ through the screen T and annular recess in the member R and then through the ports L' M³ into the pump barrel. This will avoid carrying clogging impurities 55 which may be in suspension in the liquid fuel into each unit and in the same manner will avoid the forcing of air bubbles with the fuel into the high pressure pump barrel.

Within the pump barrel M is the pump plunger 60 X which is attached at its outer end to a head X' slidably within the casing L and actuated by a suitable mechanism such as a tappet X². A spring Y sleeved around the barrel M and between the same and the casing L abuts at one

end against a shoulder in the member L thereby forming a means for returning the plunger in the barrel.

With the construction as above described in operation the actuation of the tappet X² will move the plunger X inwardly in the barrel M and as the end of said plunger passes the ports M³ will force the fluid within the barrel past the check valves N and N' and through the passage A² into the casing A from which it will be expelled through the restricted space between the annular knife edge H and the flaring nozzle E'. Assuming that all of the space between the barrel and the discharge end of the nozzle has once been completely filled with the liquid fuel, it is evident that the quantity of liquid discharged from the nozzle will correspond exactly to the displacement of the plunger after the ports M³ are closed. This is primarily due to the fact that the structure between the nozzle and the plunger is rigid and of such strength that the high hydraulic pressure on the liquid cannot produce any distortion. Also the presence of the double check valves N N' insures the cutting off of communication between the nozzle and the pump 100 barrel prior to the retraction of the plunger. As before stated, the supply of fuel to the several cylinders is by way of the lateral channels R' in each succeeding unit and this tends to carry away any air bubbles or other impurities held 105 in suspension instead of forcing them into the pump barrel.

What I claim as my invention is:

1. A rigid fuel injection unit for an internal combustion engine comprising a rigid casing 110 member carrying a nozzle, means for imposing a high resistance to the passage of fuel through said nozzle, a second rigid casing member carrying a ported pump barrel and a plunger reciprocable past the port, a bushing in the second 115 casing, one-way valve means located in the end of the bushing nearest the first casing member and closing against said bushing, a second one-way valve located in the end of the pump barrel 120 and closing thereagainst, said first mentioned casing member being rigidly secured to but detachable from said second mentioned casing member and firmly clamping the bushing against the barrel, said bushing and first mentioned casing member together forming an inextensible 125 passageway for the fuel from said barrel to said nozzle.

2. A rigid fuel injection unit for an internal combustion engine comprising a rigid casing member carrying a nozzle, means for imposing a high resistance to the passage of fuel through 130 said nozzle, a second rigid casing member carrying a ported pump barrel and a plunger reciprocable past the port, a bushing in the second casing, one-way valve means located in the end 135 of the bushing nearest the first casing member and closing against said bushing, a second one-way valve located in the end of the pump barrel and closing thereagainst, said first mentioned casing member being rigidly secured to but detachable from said second mentioned casing member and firmly clamping the bushing against the barrel, said bushing and first mentioned casing member together forming an inextensible 140 passageway for the fuel from said barrel to said nozzle, and said passageway having relatively short length and relatively small cross section. 145
